CLAIM

The ornamental design for combined chopsticks with rest, as shown and described.

DESCRIPTION

FIG. 1 is a perspective view of combined chopsticks with rest, showing our new design;

FIG. 2 is a top view thereof;

FIG. 3 is a bottom view thereof;

FIG. 4 is a right view thereof, with the left view being a mirror image;

FIG. 5 is a rear view thereof;

FIG. 6 is a front view thereof;

FIG. 7 is a cross section view thereof, taken along line 7-7 in FIG. 6. This view reveals a gap between a chopstick and a rest; and,

FIG. 8 is a perspective view thereof, shown in use with the chopsticks in a disassembled condition.
